Des. 241,826
Patented Oct. 12, 1976

241,826

BOAT

William I. B. Crealock, 657 W. 19th St.,
Costa Mesa, Calif. 92627

Filed Jan. 19, 1973, Ser. No. 325,068

Term of patent 14 years
The term of this patent subsequent to Apr. 25, 1986,
has been disclaimed

Int. Cl. D12—06

U.S. Cl. D12—64

FIG. 4

FIG. 6

FIG. 5

FIG. 1 is a side elevational view of the starboard side of a boat. The port side is substantially identical in appearance to the starboard side.

FIG. 2 is the same as FIG. 1 with the cabin top in a raised position.

FIG. 3 is a partial cross-sectional view taken substantially along the longitudinal center line of FIG. 1 with the rudder shown fragmentarily for convenience of illustration.

FIG. 4 is a top plan view of the boat.

FIG. 5 is an elevational view from the bow.

FIG. 6 is an elevational view from the stern.

What is claimed is:

The ornamental design for a boat, substantially as shown and described.
